(57) **CLAIM**

The ornamental design for an anchor, as shown and described.

DESCRIPTION

FIG. 1 is a front elevational view of an anchor in accordance with this invention, wherein the rear elevational view of the anchor is a mirror image of FIG. 1 and therefore not shown. FIG. 2 is a right side view of the anchor of FIG. 1, wherein the left side view of the anchor is a mirror image of FIG. 2 and therefore not shown.

FIG. 3 is a top view of the anchor of FIG. 1; and, FIG. 4 is a bottom view of the anchor of FIG. 1.
